MATRIX ROLLING MACHINE AND METHOD

Curtis S. Crafts, Oak Park, Ill., assignor to The Goss Printing Press Company, Chicago, Ill., a corporation of Illinois

Application February 6, 1934, Serial No. 709,925

18 Claims. (Cl. 101—17)

The present invention relates to a novel and improved method of and apparatus for producing stereotype matrices which are suitable for the casting of newspaper stereotype plates.

5 Objects and advantages of the invention will be set forth in part hereinafter and in part will be obvious herefrom, or may be learned by practice with the invention, the same being realized and attained by means of the instrumentalities and 10 combinations pointed out in the appended claims. the invention consists in the novel parts, construction, arrangements, combination and improvements herein shown and described.

15 The accompanying drawings, referred to herein and constituting a part hereof, illustrate one embodiment of the invention, and together with the description, serve to explain the principles of the invention.

Of the drawings:

20 Figure 1 is a fragmentary elevation, with certain parts broken away, of an illustrative embodiment of the present invention;

25 Figures 2 and 3 are diagrammatic views showing different positions of the driving mechanism during the operation of the embodiment shown in Figure 1;

Figure 4 is a vertical section taken on the line 4—4 of Figure 1; and

30 Figures 5 and 6 are fragmentary sectional views, partially diagrammatic, showing the positions of the cylinder and eccentrics during operation.

35 The present invention has for its object the provision of a novel and improved method of producing stereotype matrices by which any stretching of the matrix during its production is avoided. A further object is the provision of an improved stereotype matrix rolling machine for carrying out the method of the present invention.

40 Still another object is the provision of a stereotype matrix rolling machine in which the cylinder for pressing the flong against the form may be moved at an approximately constant but slightly varying the speed to compensate for any 45 unevenness in the back of the flong, such as might be caused by relatively large open or non-printing parts of the form.

50 In accordance with the method of the present invention, the form to be reproduced is placed on a flat, unyielding bed and is covered in the usual manner with the flong and packing sheets. When thus prepared, the form, supported on its bed, is passed beneath a pressure cylinder mounted for rolling movement over the form and which is 55 adapted to press the flong against and into the

surface of the form to produce the matrix. The pressure cylinder is preferably rotated so that its peripheral speed is approximately the same as the linear speed of the form, but this approximately constant speed of the pressure cylinder is varied slightly as required by any unevenness in the back of the flong so as to permit the cylinder to speed up slightly as the cylinder rolls into or out of a hollow corresponding to an open or non-printing part of the form. In this way, any stretching or longitudinal squeezing of the flong is avoided which would tend to cause slurs, and would normally result from movement of the cylinder and form at the same speed. After rolling of the matrix is completed, the packing is removed, the matrix is stripped from the surface of the form and may thereafter be curved and scorched in the usual manner.

55 Preferably, and in accordance with the illustrative embodiment of the present invention, the form supporting bed comprises a relatively large, heavy and flat slab of steel or other metal which is slidably mounted in a frame and is supported by a relatively large cylinder to which it is geared, the cylinder being rotatably mounted in the frame and driven by suitable power means. A second cylinder is preferably mounted immediately above the first cylinder and is driven from the first cylinder by means of gearing including a resilient or yielding means whereby the speed of the bed or form is substantially the same as the peripheral speed of the second cylinder, but the speed of the second cylinder may vary slightly due to the resilient means. Means are also preferably provided for minutely varying the distance between the flong-pressing cylinder and the bed so that the form and flong may be passed beneath the pressure cylinder and subjected to any desired degree of pressure or to no pressure at all, and other means are preferably provided for moving the pressure cylinders to different positions to accommodate different thicknesses of forms.

45 It will be understood that the foregoing general description and the following detailed description as well, are exemplary and explanatory of the invention but are not restrictive thereof.

50 Referring now in detail to the illustrative embodiment of the present invention shown in the accompanying drawings, the matrix rolling device comprises a bed 10 of relatively heavy and rigid metal which is adapted to be reciprocated in the frame 11 and is supported by means of a large cylinder 12 extending beneath the bed and 55

transversely of its line of reciprocation, as well as by small rollers (not shown) on either side of the cylinder 12, and runways 13.

Cylinder 12 is preferably geared to bed 10, and 5 for this purpose gears 14, one at either end of the cylinder, are keyed to the cylinder shaft 15, which is journalled in side frames 11, and mesh with the racks 14' secured to the under side of the bed 10.

Means are provided for driving the bed in either 10 direction, and for this purpose a gear 16 is keyed to one end of the shaft 15 and meshes with a gear 17 keyed to shaft 18 which is journalled in the side frame 11 and also in the outboard bearing carried by bracket 19. At its inner end, shaft 18 15 is keyed to a worm gear 20 meshing with a reversible, motor-driven worm 21 which is rotatably mounted by means of its shaft in bearings carried by the brackets 22 on the inside of frame 11.

As is usual in the rolling of stereotype matrices, 20 the form is supported in a chase 25 on the bed 10. The flong in a suitably moistened or otherwise plastic condition is laid over the surface of the type, plates, or other matter composing the form, and the flong 26 is then covered with some 25 cushioning material such as a sheet of fibre 27 and rubber 28.

Means are provided for pressing the flong against and into the surface of the form so that its surface receives an impression of the form 30 and is thereby changed into a matrix. As embodied, a relatively large cylinder 30 is rotatably mounted above the bed 10, preferably in line with the cylinder 12, and is adapted to be rolled over the rear face of the flong 26 with considerable 35 pressure. Cylinder 30 is rotatably mounted in the frame 11 in a manner which will be later more fully described.

Gearing is provided in accordance with the 40 present invention for rotating the cylinder 30 as the bed 10 is reciprocated, the peripheral speed of the cylinder 30 being approximately the same as the linear speed of the bed 10 and form 25. As embodied, a sprocket 32 is keyed to shaft 18 so as to be driven proportionately to the rotation 45 of cylinder 12, and cylinder 30 is provided with a similar sprocket 33 keyed to its shaft 34. For connecting the cylinders 12 and 30 together a chain 36 runs over the sprockets 32 and 33.

Means are provided for permitting slight variations in the speed of the cylinder 30 with reference to the speed of the bed 10, and for this 50 purpose idlers 40 are provided, one for each reach of the chain 36. Idlers 40 are mounted for free rotation on the ends of arms 42, which arms are 55 independently pivoted on a bushing 44, supported by bracket 19 and surrounding shaft 18.

A spring 45 is provided for resiliently urging the idlers 40 and their arms 42 away from each other, to take up slack in the chain 36 and to provide a 60 resilient drive from sprocket 32 to cylinder 30. Spring 45 is coiled about a threaded rod 46, pivoted at one end to a lug 47 on one arm 42 and at its other end passing through an aperture in a lug 48 on the other arm 42. Means are provided for 65 variably compressing the spring 45 and comprise the collar 49 and threaded hand wheel 50. As the bed 10 is moved, cylinder 30 is driven at approximately the same peripheral speed, but any 70 slight variations required in the speed of cylinder 30 are cared for by movement of one or the other arms 42 against the compression of spring 45.

Means are also provided for raising or lowering 75 the cylinder 30 into or out of pressing posi-

tion, and these means also preferably permit the cylinder to be used with forms of different thickness. As embodied, cylinder 30 is rotatably mounted by means of its shaft 34 in an eccentric sleeve 50 which, in turn, is mounted in a second eccentric sleeve 51, this second eccentric sleeve being rotatable in a suitable aperture in the frame 11. An eccentric 50 and another 51 is provided at either end of the cylinder. Eccentric 50 serves to move the cylinder to and from matrix 10 rolling position and to vary the rolling pressure, while eccentric 51 serves to move the cylinder to a position suitable for rolling matrices from type-high forms, or to a position suitable for rolling matrices from thin shells or plates 25'. 15

Means are also provided for moving the eccentrics 51 in unison with each other, and a shaft 55 is rotatably journalled in the upper part of frame 11 and carries pinions 56 which mesh with a gear 54 formed on the inner end of each eccentric 51. Hand wheels 57 are provided at the ends of shaft 55 to facilitate turning the shaft. 20

For turning eccentrics 50 in unison, a sprocket 58 is keyed to each of these eccentrics, and these sprockets are connected with sprockets 59 by means of chains 60. Sprockets 59 are mounted on a shaft 61 which is also rotatably mounted in the frame 11 and is provided at its ends with hand-wheels 62. As the roller is moved up and down, the slack in chain 36 is taken up by idlers 40 which are pressed apart by means of their compression spring 45. 30

As shown in Figures 5 and 6, the center of the eccentric 51 is at A, while the center of eccentric 50 is at B, and the center of the cylinder 30 is at C. Figure 5 shows the position of these parts when in proper relation for rolling a matrix on a thick form, such as type. Fig. 6 shows the position of these parts when properly set for rolling a matrix on a thin shell or plate. 40

The peripheral speed of cylinder 30 is, as stated above, preferably normally the same as the speed of the bed 10, and when constructed in this manner, the resiliently mounted idlers 40 permit the cylinder 30 to accelerate as it passes over any uneven parts in the back of the flong, while the flat portions of the back of the flong normally require deceleration of the cylinder to prevent any stretching of the mat. This acceleration and deceleration of the cylinder 30 is accompanied by a shifting of the arms 42 and idlers 40 to one side or the other, causing them to move from the position shown in Figure 2 to more or less the position shown in Figure 3, or vice versa. 50

However, the peripheral speed of the cylinder 30 may be made slightly greater than the speed of the bed 10, and in this case any unevenness in the back of the flong will cause the chain 36 to be tightened on one side, while flat portions of the back of the flong will allow the chain to return to its normal condition. 60

The invention in its broader aspects is not limited to the specific mechanisms shown and described but departures may be made therefrom within the scope of the accompanying claims without departing from the principles of the invention and without sacrificing its chief advantages. 65

What I claim is:

1. The method of forming a stereotype matrix which includes positioning a flong over the form and resiliently urging a cylinder over the flong while pressing the flong against the surface of 75

- the form by the cylinder, whereby the speed of the cylinder is varied to compensate for any unevenness in the back or top of the flong. 5
2. The method of forming a stereotype matrix which includes positioning a flong over the form, pressing the flong into the surface of the form by means of a cylinder and resiliently rotating the cylinder while it is pressing the flong against the form to roll the cylinder over the flong. 10
- 10 3. The method of forming a stereotype matrix which includes positioning a flong over the form, pressing the flong against the surface of the form by means of a cylinder, moving the flong and form beneath the cylinder and minutely varying the speed of rotation of the roller to compensate for unevenness in the back of the flong. 15
- 20 4. A matrix rolling machine including in combination a pair of cylinders spaced apart and superposed one above the other, a bed for supporting a form geared to one of said cylinders and positioned between them, and means for resiliently driving one of the cylinders including resiliently movable gearing interconnecting the cylinders so that the peripheral speed of the upper cylinder is approximately that of the bed. 25
- 30 5. A matrix rolling machine including in combination a pair of cylinders spaced apart and superposed one above the other, a bed for supporting a form geared to one of said cylinders and positioned between them, and means for resiliently driving the other of said cylinders at approximately the peripheral speed of the bed including a resiliently mounted member shiftable to vary the relative angular positions of the cylinders, the resilient drive permitting said other cylinder to accelerate or decelerate as required by unevenness in the surface of the form. 35
- 40 6. A matrix rolling machine including in combination a cylinder, a form supporting bed geared to said cylinder and adapted to support a form and superposed flong, a second cylinder for pressing the flong against said form, a chain for driving said second cylinder from the first and a resiliently mounted idler permitting said second cylinder to move independently of the first. 45
- 50 7. A matrix rolling machine including in combination a cylinder, a form supporting bed geared to said cylinder and adapted to support a form and superposed flong, a second cylinder for pressing the flong against said form, a chain for driving said second cylinder from the first and resiliently mounted idlers for taking up the slack on each reach of the chain and permitting the speed of the second cylinder to vary slightly with reference to that of the first cylinder. 55
- 60 8. A matrix rolling machine including in combination a cylinder, a form supporting bed geared to said cylinder and adapted to support a form and superposed flong, a second cylinder for pressing the flong against said form, a chain for driving said second cylinder from the first, idlers on each reach of the chain, independently movable arms on which said idlers are mounted, and resilient means for moving said arms to take up slack in the chain and to permit the speed of said second cylinder to vary slightly with reference to that of the first cylinder. 65
- 70 9. A matrix rolling machine including in combination a pair of cylinders and a form-supporting bed, one of said cylinders serving to press a flong against the surface of a form on said bed, gearing inter-connecting said cylinders and bed for moving said cylinders at approximately the same peripheral speed as the speed of the bed, said gearing including resilient driving means for the flong-pressing cylinder whereby its speed may vary slightly while the speed of the bed and other cylinder remains constant. 75
- 10 10. A matrix rolling machine including in combination a cylinder, a form supporting bed geared to said cylinder and adapted to support a form and superposed flong, a second cylinder for pressing the flong against said form, a sprocket driven by said first cylinder, a chain connecting said sprocket and second cylinder and resilient means permitting the speed of said second cylinder to vary slightly with reference to that of the first. 15
- 20 11. A matrix rolling machine including in combination a cylinder, a form supporting bed geared to said cylinder and adapted to support a form and superposed flong, a second cylinder for pressing the flong against said form, a sprocket driven by said first cylinder, a chain connecting said sprocket and second cylinder, independent resiliently mounted arms and idlers mounted on said arms for taking up slack in said chain and permitting slight variations in the speed of said second cylinder. 25
- 30 12. A matrix rolling machine including in combination a form supporting bed, a cylinder to roll a flong against said form, means for variably positioning said cylinder in either of two positions to accommodate forms of different thicknesses, means for moving the cylinder to impression position in either of said first positions and means for driving said cylinder in any of said positions at approximately the speed at which the bed is moved beneath said cylinder, said driving means including resilient means permitting the speed of said cylinder to vary slightly with reference to that of the bed. 35
- 40 13. A matrix rolling machine including in combination a form supporting bed, a cylinder to roll a flong against the surface of said form, means for rotatably mounting and variably positioning said cylinder including a pair of eccentrics at either end of the cylinder, one eccentric being mounted in the other, and means for driving said cylinder at substantially the same speed as the bed, said driving means including a chain and resiliently mounted idlers for taking up slack in the chain and permitting slight variations in the speed of the cylinder. 45
- 50 14. A matrix rolling machine including in combination a form supporting bed, a cylinder to roll a flong against the surface of said form, a second cylinder directly beneath the first cylinder and supporting the bed, and means for variably positioning said cylinder with reference to said bed, including means for moving the cylinder to either of two positions to accommodate thick or thin forms and means for moving the cylinder to impression position or to clear the flong in either of said two positions. 55
- 60 15. A matrix rolling machine including in combination a form supporting bed, a cylinder to roll a flong against said form and means for rotatably mounting and variably positioning said cylinder including an eccentric at either end of the cylinder and in which the cylinder is rotatably journaled and other eccentrics in which said first eccentrics are mounted. 65
- 70 16. A matrix rolling machine including in combination a form supporting bed, a driving shaft geared to said bed, a gear fixed on said shaft, a cylinder for pressing flong against a form on said bed, a gear fixed on the shaft of said cylinder, 75

driving connections between said gears for driving said cylinder at approximately the speed of the bed, said connections including means for permitting slight variations in the speed of said cylinder with respect to the bed.

17. A matrix rolling machine including in combination a form supporting bed, a driving shaft geared to said bed, a gear fixed on said shaft, a cylinder for pressing flong against a form on said bed, a gear fixed on the shaft of said cylinder, driving connections between said gears for driving said cylinder at approximately the speed of the bed, said connections including means for permitting said cylinder to slightly accelerate or

decelerate it as by reason of variations in the surface of the form.

18. A matrix rolling machine including in combination a form supporting bed, a driving shaft geared to said bed, a gear fixed on said shaft, a cylinder for pressing flong against a form on said bed, a gear fixed on the shaft of said cylinder, driving connections between said gears including a sprocket chain and means responding to differences in the rolling pressure for varying the length of the two reaches of the sprocket chain to cause small variations in the speed of said cylinder.

CURTIS S. CRAFTS.
